United States Patent Office

Des. 181,041

Patented Sept. 24, 1957

181,041

PRUNING KNIFE

James R. Chokas, Arlington, Tex.

Application March 6, 1956, Serial No. 40,480

Term of patent 14 years

(Cl. D22—3)

Fig. 1.

Fig. 2.

Fig. 3.

Figure 1 is a side elevational view of a pruning knife showing my new design;

Figure 2 is a side elevational view thereof as it appears with the blade in closed position; and

Figure 3 is a top edge view of the pruning knife as shown in Figure 2.

The side opposite to that shown in Figures 1 and 2 presents an identical appearance.
